(57) **CLAIM**

The ornamental design for a base station for robot, as shown and described.

DESCRIPTION

FIG. 1 is a front perspective side view of the base station for robot;

FIG. 2 is a front view of the base station for robot;

FIG. 3 is a top view of the base station for robot shown in mating relation with a portion of a cylindrically-shaped robot, shown in uneven broken line;

FIG. 4 is a bottom view of the base station for robot;

FIG. 5 is a rear view of the base station for robot;

FIG. 6 is a left side of the base station for robot; and,
FIG. 7 is a right side view of the base station for robot shown in mating relation with a portion of a cylindrically-shaped robot, shown in uneven broken lines.

Elements of the base station for robot and portions of a mating robot shown in uneven broken lines are for illustrative purposes only and form no part of the claimed design.
